CATALYTIC OXIDATION OF AROMATIC HYDROCARBONS IN PRESENCE OF NITROALKANES

Herman Pines and Bruno Kvetinskas, Chicago, Ill., assignors to Universal Oil Products Company, Chicago, Ill., a corporation of Delaware

No Drawing. Application June 26, 1946,
Serial No. 679,574

9 Claims. (Cl. 260—592)

1

This invention relates to a process for oxidizing aromatic hydrocarbons and particularly benzene hydrocarbons.

An object of this invention is to produce aromatic alcohols and aromatic carbonyl compounds.

Another object of this invention is to oxidize an aromatic hydrocarbon in the presence of a nitrated aliphatic hydrocarbon.

Still another object of this invention is to oxidize an aromatic hydrocarbon by means of an oxygen-containing gas in the presence of a nitroalkane.

A further object of this invention is to oxidize an alkyl benzene hydrocarbon in the presence of a catalytic amount of a nitroalkane.

A still further object of this invention is to oxidize an aromatic hydrocarbon in the presence of a catalyst comprising a metal selected from the group consisting of the metals having atomic numbers of from 23 to 30, inclusive, and in the presence of a nitroalkane.

One specific embodiment of the present invention relates to a process for oxidizing an aromatic hydrocarbon which comprises reacting said aromatic hydrocarbon and an oxygen-containing gas in the presence of a nitroalkane.

A further embodiment of this invention relates to a process for oxidizing an aromatic hydrocarbon which comprises reacting said aromatic hydrocarbons and an oxygen-containing gas in the presence of a nitroalkane in a reaction zone containing a metal selected from the group consisting of the metals having atomic numbers of from 23 to 30, inclusive.

A still further embodiment of this invention relates to a process for oxidizing an alkyl benzene hydrocarbon which comprises reacting said benzene hydrocarbon, a nitroalkane, and an oxygen-containing gas in a reaction zone containing a refractory packing material composited with a metal selected from the group of metals having atomic numbers of 23 to 30, inclusive.

We have found that aromatic hydrocarbons and particularly aromatic hydrocarbons of the benzene series are oxidized readily by an oxygen-containing gas in a reaction zone containing a refractory packing material upon which a small amount of a metal or a metal oxide is deposited. The oxidation process is also catalyzed by a nitroparaffin which may be mixed with the aromatic hydrocarbon charged to the process or it may be introduced to the reaction zone by other means.

Aromatic hydrocarbons such as toluene, xylene, ethyl benzene, curnene, cymene, a butyl benzene, and other alkylated benzenes, naphthalene, an

alkylated naphthalene, and other polynuclear and alkylated polynuclear aromatic hydrocarbons which are oxidized by our process have at least 7 carbon atoms per molecule and include alkyl benzene hydrocarbons and polycyclic aromatic hydrocarbons.

Our process is carried out in the presence of a liquid catalyst, a solid catalyst, and preferably in the presence of both a liquid catalyst and a solid catalyst, the latter employed as a reactor packing material.

Liquid catalysts which we employ comprise nitroaliphatic hydrocarbons and particularly the nitroalkanes which are also referred to as the nitroparaffins. The following table gives the boiling points and specific gravity of some of the nitroparaffins used in our process, although other nitroparaffins containing more than four carbon atoms per molecule, and particularly the nitropentanes are also useful as oxidation catalysts.

Compound	Boiling Point, °C.	Specific Gravity at 20° C.
Nitromethane	101	1.139
Nitroethane	114	1.052
1-Nitropropane	132	1.003
2-Nitropropane	120	0.992
1-Nitrobutane	151	0.975

30 The solid catalysts which we use in our process as packing material in the oxidation reactor comprise metals with atomic numbers of 23 to 30, inclusive, thus including the metals vanadium, chromium, manganese, iron, cobalt, copper, and zinc, supported by a refractory packing material such as crushed firebrick, granular pumice, quartz chips, crushed porcelain, silica, or other refractory granular materials which do not have a harmful influence upon the oxidation reaction.

35 Such composites of a refractory packing material and a metal are produced preferably by dissolving a metal salt of an organic acid and particularly a metal salt of a long chain fatty acid, such as a metal stearate, in a normally liquid aromatic hydrocarbon which is oxidized by our process. Thus from about 0.1 to about 0.5% by weight of metal salt is dissolved in a normally liquid aromatic hydrocarbon and the resultant solution is then conducted to a heated reaction zone containing a refractory packing material in granular form or small particles. Oxygen, air, or another oxygen-containing gas is charged simultaneously to the reaction zone containing the packing material in order to effect oxidation of the aromatic hydrocarbon. During this oxidation

treatment, the metal salt of the organic acid which is dissolved in the aromatic hydrocarbon and charged to the reaction zone is decomposed therein and the resultant metal oxide is deposited upon the refractory packing material to form a highly active oxidation catalyst. The metal salt, which is sometimes referred to as a metal soap, is thus introduced either continuously or intermittently as desired in order to maintain in the reaction zone an amount of metal oxide sufficient to catalyze the oxidation of the aromatic hydrocarbon charged thereto together with the aforementioned liquid catalyst comprising a nitroparaffin or a mixture of nitroparaffin.

Our oxidation process may be carried out in either a batch operation or a continuous type of operation, although the latter is generally preferred. The oxidation treatment is effected at a temperature of from about 50° to about 200° C. and at a pressure of from substantially atmospheric to about 100 atmospheres. The oxidizing medium employed comprises air, oxygen, a mixture of air and oxygen, or either air or oxygen diluted with an inert gas.

The nitroalkanes which are the liquid catalysts preferred in our process may be substituted or partially substituted by an oxide of nitrogen, particularly nitrogen dioxide, nitrogen trioxide, and nitrogen tetraoxide.

The following examples are given to illustrate the results obtained in this process, although the data presented are not introduced with the intention of restricting unduly the broad scope of the invention.

Example I

Cumene containing 0.5 mole per cent of a nitropentane and air were charged simultaneously to a steel reactor, containing granular pumice supporting 0.9% by weight of manganese oxide and maintained at a temperature of 150° C. and operating at a pressure of 35 atmospheres. The mixture of cumene and nitropentane was charged at a rate corresponding to an hourly liquid space velocity of 1.6 and the amount of air introduced to the reaction zone was such that the molar ratio of oxygen to hydrocarbon in the reaction mixture was 3. By this treatment, 39 mole per cent of the cumene was oxidized per pass and on a recycle basis yielded 56 mole per cent of acetophenone and 21 per cent of dimethylphenylcarbinol.

Example II

In another run, cumene was mixed with 2 mole per cent of nitromethane and the resultant solution was subjected to the oxidation treatment as described in Example I. Twenty-nine per cent of the cumene was converted per pass with the formation on a recycle basis of 45 per cent of acetophenone and 30 per cent of dimethylphenylcarbinol.

The nature of the present invention and its utility are evident from the specification and examples, although neither section is introduced to limit unduly the generally broad scope of the invention.

We claim as our invention:

1. A process for oxidizing an aromatic hydro-

carbon of at least 7 carbon atoms per molecule which comprises reacting said hydrocarbon with an oxygen-containing gas in the presence of a nitroalkane.

5 2. A process for oxidizing an aromatic hydrocarbon of at least 7 carbon atoms per molecule which comprises reacting said hydrocarbon with an oxygen-containing gas in the presence of a nitroalkane and an oxide of a metal having an atomic number of from 23 to 30, inclusive.

10 3. A process for oxidizing an aromatic hydrocarbon of at least 7 carbon atoms per molecule which comprises reacting said hydrocarbon with an oxygen-containing gas in the presence of a nitroalkane at a temperature of from about 50° C. to about 200° C.

15 4. A process for oxidizing an aromatic hydrocarbon of at least 7 carbon atoms per molecule which comprises reacting said hydrocarbon with an oxygen-containing gas at a temperature of from about 50° C. to about 200° C. in the presence of a nitroalkane and an oxide of a metal having an atomic number of from 23 to 30, inclusive.

20 5. The process as defined in claim 1 further characterized in that said hydrocarbon is an alkyl benzene.

25 6. The process as defined in claim 2 further characterized in that said hydrocarbon is an alkyl benzene.

30 7. The process as defined in claim 1 further characterized in that said hydrocarbon comprises cumene.

8. The process as defined in claim 2 further characterized in that said hydrocarbon comprises

35 cumene.

9. A process for producing dimethylphenylcarbinol and acetophenone which comprises reacting cumene and air in the presence of nitromethane at a temperature of from about 50° to about 200° C. and at a pressure of from about 1 to about 100 atmospheres in a reaction zone containing a granular composite of manganese oxide and pumice.
